CLAIM

The ornamental design for an oven range, as shown and described.

DESCRIPTION

1. Oven range
- 1.1 : Perspective
- 1.2 : Front
- 1.3 : Back
- 1.4 : Left
- 1.5 : Right
- 1.6 : Top
- 1.7 : Bottom
- 1.8 : Reference

Reproduction 1.8 is a reference view showing a state of the front surface glass door changed into the so-called “see-through door” by means of a sensor for detecting approach of and/or contact of person, and forms no part of the claimed design.

1 Claim, 8 Drawing Sheets(56)
